TEMPORARY COVER FOR BATHTUBS AND OTHER PLUMBING FIXTURES

Filed April 29, 1930

UNITED STATES PATENT OFFICE

GEORGE M. GOULD, OF BROOKLYN, NEW YORK

TEMPORARY COVER FOR BATHTUBS AND OTHER PLUMBING FIXTURES

Application filed April 29, 1930. Serial No. 448,191.

My invention relates to temporary protective covers for bath tubs, water closets, wash basins, and other plumbing fixtures which are usually positioned before the tiling or plas-

tering of the room in which they are placed is done.

The object of the invention is to provide a cover having concealed locking means which cannot be tampered with by any unauthorized 10 person when placed in position on a fixture.

A further object is to provide a light weight cover, adapted in size and shape to the particular purpose for which it is intended, and having locking means to secure 15 the cover in a rigid and secure manner until the locking means are released.

I show such a cover adapted for a bath tub, embracing the novel locking features, it being only necessary to alter the shape and size of 20 the body of the cover to have it conform to and suit other plumbing fixtures.

In the accompanying drawings,

Figure 1 is a longitudinal view of the cover in section on line O—O of Figure 2 with the 25 locking means folded down as in a locking position;

Figure 2 is a bottom view, the locking means being folded up against the cover as in handling or shipping;

Figure 3 is an enlarged view on line X—X of Figure 2 showing the cover in position and locking on the inner surface of a bath tub;

Figure 4 is an enlarged detail showing one-half of the locking means, and

Figure 5 is an enlarged view of the folding bracket and socket which supports the locking device.

Similar numbers of reference refer to like parts in the several views.

The flat cover 1 is made of several layers of thin wood, cross grained and glued together commonly known as "panel board", and to give it additional strength and rigidity to prevent warping three wooden strips 2, 2', 2'' are fastened at points shown, the centre strip 2' extending further outwardly from the board than the other two strips. Two wire rods or cables 3, 3' are suitably anchored

in the outer strips, passing over the centre strip 2' thus forming when bent a brace to

strengthen centre and support any ordinary weight liable to be placed upon the cover, such as a man standing on it while applying the tiling, plaster or paint.

The folding and locking mechanism is fastened to the centre strip, 2', by means of two right angle pieces 4 reciprocating arms 5 preferably cast integral with a square body 5' having a square lateral opening 5'' for the passage of a suitably shaped rod 6 threaded at the free end 6' for connection with a turnbuckle 7 tapped to suit the thread,—left and right,—at opposite ends as shown. A thumb screw 8 acts as a pivot and holds the arm 5 in a fixed position, either folded against the board for shipping as shown in Figure 2 or extended for use in locking Figure 3.

Thumb screw 8' holds the rod 6 securely in position. At the outer end of the rod 6 a hardwood block 9 is suitably fastened to a metal plate 10. A soft rubber pad 11 of so-called "non-skidding" rubber is cemented to the hardwood block, the rubber being fairly thick so that when compressed it will conform itself to the angle or outline of the tub without slipping.

The turnbuckle 7 is operated by means of a sliding rod 12, having a head on each end or central extensions 7' may be cast integral with the turnbuckle to afford a leverage for rotating the same, this operation being done through a small door 13 in the cover just large enough to permit the entrance of a hand; 13' is the striking plate for the door. So that this door will not be opened, when closed, by any unauthorized person, the hinges, 14, are riveted on, the door being fastened down by a screw 15 the head of which is sealed by wax or a wire and lead seal 16 may be used to prevent opening the door and tampering with the locking means.

Around the inner surface of the wooden cover, near the edges thereof, a felt strip 17 of suitable width is secured to prevent abrasion of the surface of the tub T.

From the foregoing description of the construction the operation is evident.

The size of the body of the cover in every case is made to suit the size or shape of the

tube or fixture to which it is to be applied, and when placed in position, the locking means are unfolded and tightened into position by the thumb screws 8, the thumb screws 8' being released. The turnbuckle is rotated until the rubber pads are firmly compressed against the inner side or wall of the tub, this being done by passing the hand through the door, and when thus fastened, the thumb screws 8' are advanced against the rods 6, as an additional fastening means. The square sections of said rods, slidably mounted in the square opening 5" prevents the rod from turning when the turnbuckle is operated. When the cover is thus secured to the tub, the hand door is closed and screws or seal or both are applied.

The felt strip which extends outwardly from the cover is laid down over the surface of the tub,—as shown by dotted lines in Figure 3,—and can be fastened by adhesive tape or other means to protect the surface and prevent abrasion.

To remove the cover when the tiling or finishing of the room is completed, the seal is broken, the hand door opened and operation described above is reversed thus enabling the cover to be removed and used elsewhere where conditions are favorable.

To suit the several sizes and styles of tubs, basins and the like, covers of a proper size must be provided, the locking means however being identical in all cases.

The covers being made of wood are light, easily handled and cheaply transported. To protect all the wooden surface from wet or moisture several coats of water resisting paint is applied.

Such being my invention what I claim is:

1. A cover for bath tubs and the like comprising a relatively light elongated body, and truss members at the under surface of said body and anchored adjacent each end thereof, and means for throwing said truss members outwardly away from said body intermediate the ends thereof.

2. A cover for bath tubs and the like comprising a relatively light elongated body, truss members at the under surface of said body and anchored adjacent each end thereof, and means for throwing said truss members outwardly away from said body intermediate the ends thereof, and wall engaging locking means carried by said last mentioned means.

3. A cover for bath tubs and the like comprising a relatively light elongated body, truss means at the under surface of said body, and wall engaging locking means carried by an element of said truss means.

4. A closure device of the class described comprising a body, fixture-wall-engaging locking means carried by the under surface of said body, manual means also carried at the under surface of said body for positively ac-

tuating said locking means to and from operative position, and a sub-closure controlled opening affording access to said actuating means and for concealing the same.

5. A closure device of the class described comprising a body, fixture-wall-engaging locking means carried by the under surface of said body, manual means also carried at the under surface of said body for positively actuating said locking means to and from operative position, a sub-closure controlled opening affording access to said actuating means, said sub-closure normally concealing the same, and a swingable support for said locking means and its actuating means, said support being carried by said body whereby said locking and actuating means can be folded against said body when the device is not in use.

6. A closure device of the class described comprising a relatively thin and elongated panel-like body, fixture-wall-engaging locking members beneath said body, one adjacent each side of said body, swingable supports for said locking members and carried by the under surface of said body, actuating means for said locking members and connecting the inner ends thereof, and friction means for holding said locking member support in a predetermined position.

7. A closure device of the class described comprising a relatively thin and elongated panel-like body, fixture-wall-engaging locking members beneath said body, one adjacent each side of said body, swingable supports for said locking members and carried by the under surface of said body, actuating means for said locking members and connecting the inner ends thereof, said locking member supports having guide portions within which said locking members work, and means operable to lock said locking means against movement relative to the guide portions of said locking member supports.

8. A closure device of the class described comprising a relatively thin and elongated panel-like body, fixture-wall-engaging locking members beneath said body, one adjacent each side of said body, swingable supports for said locking members and carried by the under surface of said body, actuating means for said locking members and connecting the inner ends thereof, said locking member supports having guide portions within which said locking members work, means operable to lock said locking means against movement relative to the guide portions of said locking member supports, and said body having a marginal fixture-rim protecting pad portion at its under surface, said pad portion being adapted to extend beyond the edge of said surface and having an adhesive surface, said surface being adapted to be stuck to the side wall of the fixture whereby to protect the same.

9. A closure device of the class described

comprising a relatively thin and elongated panel-like body, fixture-wall-engaging locking members beneath said body, one adjacent each side of said body, swingable supports for said locking members and carried by the under surface of said body, actuating means for said locking members and connecting the inner ends thereof, said locking member supports having guide portions within which said locking members work, means operable to lock said locking means against movement relative to the guide portions of said locking member supports, and said body having an opening afforded access to said locking member actuating means, and a closure for said opening.

In testimony whereof I affix my signature.
GEORGE M. GOULD.
